INTERNAL SCRATCHER FOR MATCH BOXES

Filed Nov. 23, 1929

UNITED STATES PATENT OFFICE

1,985,837

INTERNAL SCRATCHER FOR MATCH BOXES

Rodney S. Pullen, Philadelphia, Pa., assignor to
Pullenlite Company, Philadelphia, Pa., a corpora-
tion of Pennsylvania

Application November 23, 1929, Serial No. 409,312

2 Claims. (Cl. 206—34)

My invention relates to match boxes.

A purpose of my invention is to apply ignition material to the interior of a match box in order to protect the ignition material from dampness.

5 A further purpose is to provide a match box having a slideable match holder and a cover portion with a stop projecting downwardly to limit the movement of the slideable portion.

10 A further purpose is to provide a match box adapted to be placed in a striking position when the box is closed and which strikes as the match is withdrawn.

15 A further purpose is to facilitate the use and portioning of the ignition of the so-called headless matches, thus effecting a saving in the volume of match head material required.

20 A further purpose is to apply ignition material to the interior of the match holder, preferably at the end of the carrier or cover.

25 A further purpose is to provide more space for advertising on the exterior of the match box.

Further purposes will appear in the specification and in the claims.

I have elected to illustrate several forms of 25 my invention, selecting however forms which are practical and efficient in operation and which well meet the needs of service.

Figure 1 is a perspective view of a match box in open position, showing my invention applied thereto.

Figure 2 is a perspective view similar to Figure 1 but in closed position, illustrating a match in position for striking.

Figure 3 is a transverse section taken on the line 3—3 of Figure 2.

Figure 4 is a vertical section taken on the line 4—4 of Figure 3.

Figure 5 is a view similar to Figure 4, but with the match carrier in open position and in engagement with a stop.

Figure 6 is a view similar to Figure 4 with a match shown in position for striking.

Figure 7 is an inverted perspective view of the lid or cover, showing the opposite end to that seen in Figure 1.

Figure 8 is a perspective view similar to Figure 1 showing a modification.

Figure 9 is a perspective view similar to Figure 2 showing a modification.

50 Figure 10 is a perspective view of the match box seen in Figures 8 and 9, but looking in the opposite direction and illustrating a match of the head type.

Like numerals refer to like parts in all figures.

55 My invention contemplates applying ignition

material to the interior of the trays or covers of match boxes, so that the user may select a single match when the box tray is in an open position and then pull the cover over the tray, allowing the match to project through the end of the box, or from the top of the tray, the match head being held against the ignition material. By a further movement of the match outwardly the match is then lighted against the igniting material.

5 In Figure 1, I show a match box 10 comprising a match tray 11 and a cover 12.

The tray 11 is provided with a bottom 13, sides 14 and 15 and ends 16 and 17 and is open at its top 18.

10 A cover 12, provided with top and bottom portions 19 and 20, side walls 21 and 22 and open ends 23 and 24, slides longitudinally over the tray 11, allowing for filling of the match tray and also for opening of the box by the user.

15 In assembling the package as a unit, matches are placed in the tray 11, which is then inserted into the cover 12 so that the ends 16 and 17 of the tray are flush with the open ends 23 and 24 of the cover as in existing match boxes for safety 25 matches or for matches which strike on any surface.

20 A wire 25 is placed upon the top 19 of the cover in one form of the invention so that one end 26 of the wire projects downwardly to form a stop against which the end 16 of the tray engages when the carrier 11 is slid outwardly. The opposite end 27 of the wire is held in the top 19 of the cover, after which a layer of paper is glued over the top 19 and the wire to hold the wire 25 in place.

25 I preferably place a strip or coating of ignition material 28 under the top 19 of the cover at the end where the tray 11 is projected outwardly, but it also may be placed on the interior of the tray 40 and as shown at 28' in Figure 8.

With my package, when it is desired to strike a match, the user can pull out the tray and take a match in the fingers and, without taking the match fully out of the tray, close the cover so that the match will project out of the box and its inner end or head will engage the ignition material as shown in Figure 2. By a quick pull of the match, it may then be lighted as the match is 45 withdrawn from the box.

50 In the form shown in Figures 8 and 9 the ignition material is placed on the end of the carrier. The user may place the match in a vertical position with the head or inner end against the igni- 55

tion material and close the box, then, by a quick pull of the match, cause the match to light.

In the form shown in Figures 1 to 7 inclusive, the box is allowed to open such a distance only as will be ample to permit the fingers properly to enter the box and to withdraw a match. This opening distance is determined by the stop 26, but in the form of Figures 8 and 9 the stop is omitted.

10 By placing the ignition material inside the box, greater advertising space may be obtained if so desired, but in some cases it may be desired to place the ignition material both on the inside and outside of the box and I have illustrated in Figures 8 and 9 the ignition material in both places.

15 The positions of ignition in the tray of Figure 8 and on the inside of the covers of Figures 1 to 7 is not in the least inconsistent and both are shown in Figure 10 with which the exterior ignition material may be used or not as desired.

20 The exterior ignition material permits use of the outer box surfaces for ignition by those who prefer this use and is merely surplusage to those who take advantage of my invention to light the 25 matches against the interior ignition material.

25 My invention is applicable to matches having definite heads as indicated in Figures 10 and also to the so-called headless type of matches. Because of the constriction of the space through 30 which the matches are required to pass, it is desirable in the use of matches having heads definitely enlarged with respect to the match body, that the "head" material be made hard enough to eliminate the risk of breaking off parts 35 of the heads.

My invention is particularly suitable for so-called headless matches because there need be no end lobe of "head" of the match as the striking takes place fully upon the side of the match end.

40 This not only eliminates the necessity for a decided end lobe of match head material, but also reduces the quantity of material needed at the sides of the match ends.

5 In operation, where the striking material is located as at 28 on the inside of the end of the cover, it is desirable to limit the open movement of the tray as indicated in Figure 1 in order to prevent the head ends of the matches from engaging with the striking material. Where the striking material is located as at 28' on the inside of the end of the tray precaution of this character is not required.

10 In either event, whether the match be struck by movement in the direction in the length of the match in Figure 2 or in the direction of the length of the match in Figure 9 the resilience of the match box material assists in maintaining 15 desirable continued contact of the side of the head end of the match—whether the match be headed or headless—and the striking material within the box.

20 In view of my invention and disclosure variations and modifications to meet individual whim or particular need will doubtless become evident to others skilled in the art, to obtain part or all of the benefits of my invention without copying the structure shown; and I, therefore, claim all such insofar as they fall within the reasonable 25 spirit and scope of my invention.

Having thus described my invention, what I claim as new and desire to secure by Letters Patent is:

30 1: A match box comprising the usual thin cover of sheet material, a tray sliding therein and including sides, bottom and ends of thin material having ignition material upon the inside of one thin end of its tray.

35 2: A safety match box of standard size having a cover and a tray having end, side and bottom walls and sliding therein, in combination with matches within the tray, having their heads located all at one end of the tray, ignition material directly on the inside of one of the end walls at that end of the tray farthest from the heads of the matches.

RODNEY S. PULLEN.
